UNITED STATES PATENT OFFICE.

JOSEPH STOLZ, OF NEW YORK, N. Y.

CLOTHES-LINE ATTACHMENT FOR WINDOWS.

1,200,539.

Specification of Letters Patent. Patented Oct. 10, 1916.

Application filed March 10, 1916. Serial No. 83,330.

To all whom it may concern:

Be it known that I, JOSEPH STOLZ, a citizen of the United States, and residing at New York, in the county of New York and 5 State of New York, have invented certain new and useful Improvements in Clothes-Line Attachments for Windows, of which the following is a specification, such as will enable those skilled in the art to which it applies 10 to make and use the same.

This invention relates to clothes line attachments for windows, and the object thereof is to provide an improved device of this class designed for use in connection with an 15 endless line and with a supplemental support at a predetermined distance from the window and provided with a pulley around which the line is passed; a further object being to provide a clothes-line attachment 20 of the class specified by means of which the line may be drawn inwardly of the window so as to facilitate the placing of articles to be dried thereon and then moved outwardly of the window so that the attachment will 25 not interfere with the closing of the sashes, or the bottom sash of the window; a further object being to provide a device of the class specified whereby all parts of the line will be held in a taut condition at all times regardless 30 of the different position or positions of the separate parts of the attachment; and with these and other objects in view the invention consists in a clothes line attachment for windows constructed and operating 35 as hereinafter described and claimed.

The invention is fully disclosed in the following specification, of which the accompanying drawing forms a part, in which the separate parts of my improvement are 40 designated by suitable reference characters in each of the views, and in which:—

Figure 1 is a vertical sectional view of a window frame and showing the face of one side of the frame and a section of the bottom of the frame, and showing my improved clothes line attachment applied thereto with the parts thereof folded so as to permit the closing of the sashes, or the bottom sash; Fig. 2 a similar view showing the bottom 45 sash raised and the parts of the attachment in the position they assume in the operation of attaching the articles to be dried to the line; Fig. 3 a detail view looking in the direction of the arrow 3 of Fig. 2 and on an enlarged scale; Fig. 4 a transverse sectional view on the line 4—4 of Fig. 2; Fig. 5 a sec-

tion on the line 5—5 of Fig. 3; and Fig. 6 a section on the line 6—6 of Fig. 2 and on an enlarged scale.

In the drawing forming part of this specification, I have shown at *a* one side of a window frame, and said side of the frame is provided with the usual vertical spaces *a*² and *a*³ in which the top and bottom sashes *b* and *b*² are mounted, said spaces being formed by an outer bead strip *a*⁴, an inner bead strip *a*⁵ and an intermediate bead strip *a*⁶.

In the practice of my invention, I provide a clothes line attachment of the class specified involving a bracket frame *c* adapted to be secured to the window frame and comprising, in the form of construction shown, a vertically arranged T-bar *c*² provided at the top and bottom thereof with plates *c*³ 75 by means of which the bracket is secured to the window frame outside of the outer bead strip *a*⁴, and a central T-bar *c*⁴ arranged at right angles to the T-bar *c*² and movable through a central L-shaped keeper *c*⁵ also 80 secured to the window frame at *c*⁶, and to the T-bar *c*², and the bar *c*⁴ is movable horizontally through the L-shaped keeper *c*⁵ and another keeper *c*⁷ with which the longer arm portion of the keeper *c*⁵ is provided. 85

Mounted in connection with the bracket frame *c* is a combination toggle lever device comprising a vertically arranged member *d* and a horizontally arranged member *d*², and the vertically arranged member *d* of the toggle lever device is provided with L-shaped keepers *d*³ which are pivotally connected therewith and slidably connected with the bar *c* of the bracket frame, and the inner end of the horizontal member *d*² of the toggle lever device is connected with the inner end of the bar *c*⁴ at *d*⁴, while the outer end thereof is pivoted to the bar *c*² at *c*⁹. 95

The vertically arranged toggle lever member *d* is provided at the top and bottom thereof with pulleys *d*⁵ and *d*⁶, and the bar *c*⁴ and horizontally arranged toggle lever member *d*² are provided at their inner ends with a pulley *d*⁷, and another pulley *d*⁸ is mounted in connection with the part *c*² of the bracket frame directly over the keeper *c*⁵ through which the bar *c*⁴ passes. Another pulley *d*⁹ is mounted in connection with a suitable support *e* arranged at a predetermined distance from the window and in connection with the pulleys *d*⁵, *d*⁶, *d*⁷, *d*⁸ and *d*⁹ 105 I employ an endless line *f* which is passed 110

around the pulley d^9 and the upper part f^2 of which is passed around the pulley d^8 , then downwardly and around the pulley d^6 , then upwardly and around the pulley d^5 and 5 then around the pulley d^7 .

It will be observed that two of the central members of the part d of the combination toggle lever device also constitute a portion of the part d^2 of said combination toggle 10 lever device, said central members being extended, as shown at d^{10} , and for the purpose of manipulating the toggle lever device the inner end of the part d^2 thereof is provided with a handle d^{11} .

15 The bar c^4 is provided at its outer end with a stop device c^8 to limit the inward movement thereof and to prevent it from being detached from the bracket frame in said inner movement, and this stop device 20 is formed by separating one of the flanges from the web of said bar and folding said flange inwardly.

In Fig. 1 of the accompanying drawing the inner and lower sash b^2 is shown in its 25 closed position, and the line attachment is shown in its folded position, or in the position it assumes when the laundried articles have been placed thereon, and are drying, and this is also the position of the 30 separate parts of the device when said device is not in use. When it is desired to place articles to be dried on the line, the bottom sash is raised as shown in Fig. 2 and the bar c^4 is drawn inwardly by means of the handle 35 d^{11} , and this operation expands the parts of the attachment as shown in Fig. 2, the bar c^4 extending into the room or compartment back of the window, and with the parts of the device in this position the articles to be 40 dried are attached to the line, or the bottom part f^3 thereof and as said articles are attached to the line, said line is drawn around the pulleys of the attachment and the pulley d^9 in the direction of the arrow x , and when 45 all of the articles to be dried are attached to the line, the bar c^4 is forced outwardly into the position shown in Fig. 1, and the bottom sash of the window may be again closed, if desired.

50 From the foregoing description it will be seen that all the parts of the line are held taut at all times no matter in what position the separate parts of the combination toggle lever device may be in, and there is no necessity for taking up slack in the line or for 55 providing devices for this purpose.

While I have shown and described the preferred form of my improvement, the invention is not limited to the details of the 60 construction shown and described, and changes therein and modifications thereof may be made, within the scope of the appended claims, without departing from the spirit of the invention or sacrificing its advantages.

Having fully described my invention, what I claim as new and desire to secure by Letters Patent, is:—

1. In a line attachment for windows, a bracket frame adapted to be secured to one side of the window frame and provided with a combination toggle lever device consisting of a vertically operating member and a horizontally operating member, said horizontally operating member being formed in connection with the vertically operating member. 70

2. In a line attachment for windows, a bracket frame adapted to be secured to one side of the window frame and provided with a combination toggle lever device consisting of a vertically operating member and a horizontally operating member, said horizontally operating member being formed in connection with the vertically operating member, and said vertically operating member being provided at the top and bottom thereof with pulleys and the horizontally operating member being provided with a pulley, and said bracket frame being provided centrally thereof with a pulley. 80

3. In a line attachment for windows, a bracket frame adapted to be secured to one side of the window frame and provided with a combination toggle lever device comprising a vertically operating member and a horizontally operating member, said horizontally operating member being formed in connection with the central parts of the vertically operating member, and a bar movable horizontally through the bracket frame and with which one end of the horizontally operating member of the toggle lever device is connected. 95

4. In a line attachment for windows, a bracket frame adapted to be secured to one side of the window frame and provided with a combination toggle lever device comprising a vertically operating member and a horizontally operating member, said horizontally operating member being formed in connection with the central parts of the vertically operating member, and a bar movable horizontally through the bracket frame and with which one end of the horizontally operating member of the toggle lever device is connected, the vertically operating member being provided at the top and bottom thereof with pulleys, the inner end of the said bar being also provided with a pulley, 100 and a pulley secured in the central outer part of the bracket frame midway thereof. 110

5. In a line attachment for windows, a supporting frame adapted to be secured to one side of the window and provided centrally with a pulley, a part movable horizontally through said frame, and a combination toggle lever device comprising a vertically operating member and a horizontally operating member, separate parts of the ver- 125 130

5 tically operating member being slidably connected with said support and one end of the horizontally operating toggle lever member being connected with the inner end of said part.

6. In a line attachment for windows, a supporting frame adapted to be secured to one side of the window and provided centrally with a pulley, a part movable horizontally through said frame, and a combination 10 toggle lever device comprising a vertically operating member and a horizontally operating member, separate parts of the vertically operating member being slidably con-

nected with said support and one end of the 15 horizontally operating toggle lever member being connected with the inner end of said part, said toggle lever members and said support being provided with pulleys, substantially as shown and described.

20 In testimony that I claim the foregoing as my invention I have signed my name in presence of the subscribing witnesses this 6th day of March, 1916.

JOSEPH STOLZ.
